UNITED STATES PATENT OFFICE.

HENRY W. LEONARD, OF SYRACUSE, AND JOHN STEVENS, OF PORT BYRON,
ASSIGNORS TO THE SYRACUSE PAPER WARE COMPANY, OF SYRACUSE,
NEW YORK.

MACHINE FOR PRESSING THE BODIES OF PAPER PAILS.

SPECIFICATION forming part of Letters Patent No. 316,985, dated May 5, 1885.

Application filed July 21, 1884. (No model.)

To all whom it may concern:

Be it known that we, HENRY W. LEONARD and JOHN STEVENS, residing, respectively, at Syracuse, in the county of Onondaga, in the 5 State of New York, and Port Byron, in the county of Cayuga and State of New York, have invented a new and useful Improvement in Machines for Pressing the Bodies of Paper Pails, of which the following is a specification.

10 This invention relates more particularly to an improved machine for pressing the bodies of paper pails made of soft paper-pulp or half-stuff, for the purpose of compacting the material and removing the moisture so far as this can be accomplished by pressure. These bodies 15 are formed by winding a web of soft paper stuff upon a suitable forming-mandrel, and the bodies so formed contain a large quantity of moisture, and would be weak and unfit to 20 handle and liable to change their form, if handled and dried in this condition.

Our machine is designed to express the moisture and harden the material by a powerful pressure, thereby rendering the bodies 25 comparatively dry and strong and enabling the bodies to withstand the handling in placing them in the drying-kiln, and to be dried therein without undergoing any change of form.

Our invention consists to that end of the 30 improvements in the construction of the machine whereby the machine is rendered effective and convenient in its operation, and which will be hereinafter fully set forth, and pointed out in the claims.

35 In the accompanying drawings, consisting of three sheets, Figure 1 is a side elevation of our improved machine. Fig. 2 is a horizontal section in line $x-x$, Fig. 1. Fig. 3 is a vertical section in line $y-y$, Fig. 2. Fig. 4 is a horizontal section in line $z-z$, Fig. 3. Fig. 5 is a vertical section, and Fig. 6 a front elevation, of 40 one of the perforated pressing-sections. Fig. 7 is a top plan view of the form and pressing-sections on an enlarged scale. Fig. 8 is a side 45 elevation of the form.

Like letters of reference refer to like parts in the several figures.

A represents a circular horizontal plate, upon which the movable pressing-jaws are arranged, and which is supported by legs A'.

The lower ends of the legs A' are connected by a three-armed bridge-tree, A², which is provided at its middle with a step-bearing, a.

a' is an upright shaft resting in the bearing a and journaled with its upper end in a bearing a², formed centrally on the lower side of the plate A.

B represents a bevel gear-wheel secured to the shaft a' and meshing with a pinion, b, which is secured to the inner end of the horizontal 55 driving-shaft b'.

C represents three vertical screws arranged equidistant around the central shaft, a', and provided at their lower ends with steps, which turn in bearings c, formed on the three arms 60 of the bridge-tree A². The upper ends of the screws C are journaled in bearings c', formed on the under side of the plate A, and the screws are in this manner held against longitudinal movement while they are free to turn 70 in their bearings.

D is a gear-wheel secured to the central shaft, a', and meshing with gear-wheels D' on the several screw-shafts C, whereby the latter are rotated from the central shaft.

E represents a movable frame through which the screws C extend, and which is provided with screw-nuts e, in which the screws C work, so that by turning the screws in one or the other direction the frame E is raised or lowered.

F represents the conical form or core arranged centrally on the plate A.

G represents the pressing-jaws, and H the intermediate jaws or pressing-sections 85 surrounding the form F.

I represents an annular horizontal plate arranged over the plate A, and supported thereon by strong upright posts i. The jaws G are arranged in radial lines with the posts i and 90 slide in radial ways or guides i', formed on the plates A and I.

J represents connecting rods which pass through openings in the plate A, and are pivoted with their lower ends to the frame E and 95 with their upper ends to movable heads J', arranged between the posts i and jaws G.

j j' represent toggle links or bars connecting the heads J' with the posts i and jaws G, so that the jaws are moved toward the form 100.

Upon raising the frame E, rods J, and heads J', and from the form upon lowering said frame.

The jaws G are constructed with straight inner faces, g, which converge upwardly in accordance with the upward taper of the form F and of the pail-body to be pressed thereon.

The intermediate jaws, H, are constructed with concave inner faces which approximately 10 complete the circle around the form F. These concave faces are constructed of perforated metallic plates h, backed by concave horizontal ribs h', which are grooved vertically, so that the water which is expressed from the 15 pulp can escape freely through the perforations of the plates h and the open spaces behind the same.

The jaws H fit with their rear sides against the straight faces of the jaws G, and are provided on their backs with shanks h², which project outwardly between the jaws G and slide in radial ways h³, formed on the plates A and I.

K represents curved springs secured to the 25 rear sides of the jaws H and bearing against the rear sides of the jaws G, whereby the jaws H are held tightly against the faces of the jaws G and compelled to move backwardly with said jaws.

30 The form or core F is composed of a fixed upright central plate, f, cast on or secured to the plate A, and two movable curved segments, f', which can be raised and lowered on the fixed plate f. The latter extends diametrically through the core, and is provided at each end with two dovetail grooves, l, converging upwardly, as clearly represented in Figs. 7 and 8.

The segmental portions f' of the core F are 40 provided at both ends with dovetail tenons or tongues l', which slide in the grooves l, so that by raising the segments f' on the plate f the segments approach each other, thereby contracting the form. The outer surfaces of the 45 plate f and segments f' are so formed as to correspond in their normal position with the interior tapering form of the pail-body to be pressed. The segments f' rest upon pins m, which slide vertically in openings formed in 50 the plate A, and which are secured to a cross-head, M. The latter slides on the vertical shaft a', and is raised by a lever, N, pivoted to a bifurcated bearing, n, secured to the under side of the plate A. The outer end of the 55 lever N is depressed by a treadle, o, thereby raising the cross-head M and segments f' and contracting the form. Upon releasing the treadle, the segments f' return to their former position by their own weight.

60 The driving-shaft b' is rotated alternately in opposite directions by belts p p' or other suitable mechanism.

Upon turning the shaft b' in the proper direction to lower the frame E the jaws G and H are moved outwardly away from the form F to the required distance to permit the wet body of the pail to be placed on the form.

This being done, the movement of the driving-shaft is reversed, so as to raise the frame E and force the jaws G and H, by means of the toggle-bars j j', with great force against the wet pail-body placed on the form F. The pressure of the jaws G and H compacts the material of which the pail-body is composed and forces the water through the perforations and 75 channels of the intermediate jaws, H.

The screws C are preferably provided with deflecting-plates C', above the screw-nuts e, to protect the screws and nuts from the water.

When the pressing operation is completed, 80 the rotation of the shaft is reversed, thereby spreading the jaws G and H and releasing the pressed pail-body. The segments f' of the form F are now raised by depressing the treadle o, whereby the form is contracted and the compacted pail-body liberated, so that it can be readily removed from the form. When the pressed body has been removed, the segments f' are lowered and the machine is ready for another pressing operation.

Our improved machine exerts a powerful pressure upon the wet pail-bodies, whereby the water is quickly pressed out and the pulp so compacted that the bodies can be conveniently and safely handled, and it performs the 95 operation of pressing the bodies in a very simple, expeditious, and convenient manner.

We claim as our invention—

1. In a machine for pressing paper vessels, the combination, with movable pressing-jaws, 100 of a core or form composed of a stationary part provided with converging ways or guides and movable parts sliding in said ways or guides, whereby the form can be contracted to facilitate the removal of the pressed vessel, 105 substantially as set forth.

2. The combination, with the stationary plate f, provided with converging guides l, of the segments f', sliding on said guides, substantially as set forth.

3. The combination, with the stationary plate f, provided with converging dovetail grooves l, of the segments f', provided with dovetail tenons l', sliding in said grooves, substantially as set forth.

4. The combination, with the stationary plate f, and movable segments f', sliding on said plate, of a cross-head, M, provided with pins m, bearing against said segments, and a lever, N, whereby said cross-head can be raised, 110 substantially as set forth.

5. The intermediate pressure-jaws, H, provided with horizontal ribs h', having concave grooved faces, and concave perforated face-plates h, in combination with the straight-faced jaws G, sliding in radial ways and forming movable straight backings, whereby the perforated jaws are closed, substantially as set forth.

6. The combination, with the pressure-jaws 130 G, moving in radial horizontal guides, of the posts i, heads J', toggle-bars j j', connecting-rods J, and actuating-frame E, substantially as set forth.

7. The combination, with the pressure-jaws G, moving in radial horizontal guides, of the posts *i*, heads J', toggle-bars *j j'*, connecting-rods J, actuating-frame E, screws C, provided with gear-wheels D', and shaft *a'*, provided with a gear-wheel, D, substantially as set forth.

8. In a machine for pressing tapering paper vessels, the combination, with a central tapering core, F, constructed with movable contractile sections, of pressing-jaws G, and intermediate perforated jaws, H, surrounding the contractile central core, substantially as set forth.

9. The combination, with the supporting-plate A and annular plate I, supported thereon, of a central core, F, composed of a fixed plate, *f*, attached to the plate A and pro-

vided with converging guides *l*, and movable sections *f'*, and pressure-jaws G, and intermediate perforated jaws, H, guided between the plates A and I, substantially as set forth.

10. The combination, with the supporting-plate A and annular plate I, of the posts *i*, connecting the same, pressure-jaws G, and heads J', and toggle-bars *j j'*, connecting the jaws G with the posts *i*, substantially as set forth.

Witness our hands this 7th day of May, 1884.
